UNITED STATES PATENT OFFICE.

FREDERICK L. CRADDOCK, OF NEW YORK, N. Y.

METHOD FOR MIXING.

Original application filed July 31, 1923, Serial No. 654,825. Divided and this application filed November 19, 1926. Serial No. 149,773.

This is a divisional application divided out from my application Serial No. 654,825 for mixing devices filed July 31, 1923, and allowed May 26, 1926.

5 The object of this invention is to provide an improved method for mixing food stuffs and other liquids, fluids or solids and mixtures of various materials in tanks by creating a stream in the body of the mix having a particular direction of flow therein as will be more fully described hereafter.

10 My improved method of mixing bodies of material in tanks consists essentially of creating a substantially solid cylindrical stream of 15 the mix in the body thereof along a slanting axis approximating that indicated in the drawing. I have found such a stream to effect several useful results the combination of which provides an advanced method for 20 the efficient mixing of materials.

The solid and compacted stream should strike a surface such, for instance, as the side or bottom of a tank glancingly and in such a manner as to break up and change direction 25 abruptly, thus mixing the material then in the stream, and also inducing a flow around an axis which is intermediate the horizontal and the vertical in the material outside the stream whereby all parts of said outside material 30 successively become a part of the stream and are thoroughly mixed. The mixing is ordinarily more effective if the stream avoids the centre of gravity of the body.

The preferred construction of an apparatus 35 in which my method may be practiced and which is described hereafter, illustrates one effective instrumentality for the practicing of the method. However, this improved method may also be practiced in other apparatus, such for instance, as that described in my patent for angular fluid mixers, Number 1,548,935, issued August 11, 1925.

In my method of mixing as effected by the stream directed as in the drawing, an extremely complex movement of the mix occurs. The stream of mix has a tendency to be pulverized as it strikes the bottom and side of the tank a glancing blow, and then to so continue as to roll and move the body of the mix. Thus all parts of the mix are successively acted upon.

Referring to the accompanying drawings:

Fig. 1 is a plan view of a tank designed to contain a mix, and

Fig. 2 is a cross-section of Fig. 1 taken on 55 the line 2—2 looking in the direction of the arrows.

The tank 1 is provided with any suitable instrumentality, for instance, a propeller 25, to create a stream in the direction of the arrow A, in the body of any mix which the tank 1 may contain.

The stream thus created co-acting with the side and the bottom of the tank in an improved manner to effect a superior mixture. 65

I claim:

1. The method of mixing bodies of material which consists of creating and directing a substantially solid compacted cylindrical stream of the mix in and through the body 70 thereof along a slanting axis extending from the top of the body to the bottom thereof, said slanting axis being in a vertical plane external to the centre of the body, whereby all parts of the mix are caused successively to 75 roll, be pulverized, and thoroughly mixed.

2. The method of mixing bodies of material which consists in creating a substantially solid compacted cylindrical stream therein along a downwardly slanting axis in a vertical plane external to the centre of the body, 80 whereby all parts of the mix are caused to successively roll, be pulverized, and thoroughly mixed.

3. The method of mixing bodies of materials which consists in creating a substantially solid, cylindrical, compacted stream therein along an axis in a vertical plane external to the centre of the body, abruptly deflecting the stream to effect a mixture of the then contents of the stream and so directing the stream after deflection as to force all parts of the body to successively become a part of the stream. 85 90

4. The method of mixing bodies of materials which consists in creating a substantially solid, cylindrical, compacted stream therein along an axis in a vertical plane external to the centre of gravity of the body and also in a plane at right angles to said vertical 100 plane and external to the centre of gravity of the body, abruptly deflecting the stream to effect a mixture of the then contents of the stream and so directing the stream after deflection as to force all parts of the body to 105 successively become a part of the stream.

FREDERICK L. CRADDOCK.
